UNITED STATES PATENT OFFICE.

LEWIS S. WATRES, OF SCRANTON, PENNSYLVANIA, ASSIGNOR TO THE NATIONAL GRAPHITE LUBRICATOR COMPANY, OF SCRANTON, PENNSYLVANIA, A CORPORATION OF PENNSYLVANIA.

MEANS FOR ARRESTING LEAKS IN STEAM-SUPERHEATERS.

1,189,643.

Specification of Letters Patent.

Patented July 4, 1916.

Application filed April 19, 1913. Serial No. 762,380.

To all whom it may concern:

Be it known that I, LEWIS S. WATRES, a citizen of the United States, residing in Scranton, county of Lackawanna, State of Pennsylvania, have invented certain new and useful Improved Means for Arresting Leaks in Steam-Superheaters, of which the following is a specification.

This invention is designed more particularly for use in connection with steam superheating boilers. Well known types of such boilers are now being used to a considerable extent on railroad locomotives. In such boilers there is usually a head or manifold to which saturated steam is admitted and with or in which are coupled a plurality of superheating units. The couplings or joints of the superheating units with the manifold constitute the most vulnerable part in such a boiler for the reason that there are a plurality of such connections subject to expansion and contraction and liable therefor to develop leaks. The purpose of this invention is to arrest such leaks in their incipiency. To accomplish this there is introduced into the saturated steam an appropriate quantity of finely divided pulverized or flocculent graphite. The graphite remains unchanged by the high temperatures and is not subject to variation because of fluctuation in temperature. It deposits in all small crevices incident to an incipient leak and constitutes an efficient and durable plug, packing or stopping therefor.

It is not intended to limit the invention to an association or combination of devices of specific character. Many ways of introducing graphite into a steam engine or other driving or driven apparatus for purposes of lubrication have been proposed. Such of them as are practicable may be employed in the present invention. Thus there have been various plans for so feeding small quantities of finely divided graphite from a hopper or reservoir containing it. So far as I know, however, the best form of so feeding finely divided graphite is that disclosed in Letters Patent of the United States No. 1,017,935 granted to Lewis S. Watres February 20, 1912. In this application therefore the use of the apparatus of that patent is illustrated and the present invention shown applied to a locomotive steam superheating boiler.

In the accompanying drawings: Figure 1 is a perspective view, partly broken away, of a locomotive steam superheating boiler showing the present invention applied thereto; Fig. 2, a detached side elevation on a larger scale showing the graphite supply devices; Fig. 3, a plan view of what is shown in Fig. 2; and Fig. 4 a vertical transverse section through Fig. 2.

1 indicates the shell of a boiler; 2 the stack thereof; 3 the saturated steam pipe; 4 the manifold into which it leads; and 5 a plurality of steam superheating units connected in the bottom of the manifold. This is all well known by those skilled in the art and detailed illustrations or more specific description is unnecessary. Since the finely divided graphite is to be introduced to the openings of the various superheating units, the means for supplying it may obviously be associated directly with the saturated steam pipe or directly with the manifold, or at any point where it will be taken up by the saturated steam. In the drawing there is shown an upwardly extending tube 6 which is fitted in the steam pipe 3 just before it turns down to the manifold. This pipe extends through the top of the boiler, the joint being made steam tight. At the top the pipe opens into or carries a hollow body 7 of appropriate strength to stand the steam pressure; and within this chamber is rotatably mounted a grinding, abrading or cutting member 8 shown in this instance, as fixedly mounted upon a rotatable shaft 9 extending through the wall of the chamber being provided with suitable packing. Above the abrading member 8 is a chamber 10, formed by an extension of the casting, provided with a removable closure cup 11. As explained in the patent hereinbefore referred to, in the chamber 10 is deposited a block, stick or cylinder of compressed graphite molded under pressure with a suitable binder which block rests upon the surface of the abrading member and which, if desirable, may be pressed into more intimate contact therewith by way of a spring pressed follower 12. It will thus be seen that, while the apparatus is in operation, the graphite is fed to the steam in a continuous attenuated stream, thus insuring a thorough intermixture with the steam leading to quick

and perfect results and economy in the use of the graphite for the purpose of this invention. Since the graphite comminuting or dividing apparatus is located at a point rendering it somewhat inconvenient to actuate it by means of a mechanical connection with some moving part of the engine; or, since it may not be most convenient to operate it by means of a pressure diaphragm operating according to the general plan disclosed in the beforementioned patent, I propose to use a small turbine or impulse motor operated by steam from the boiler and located in appropriate contiguity to the graphite abrading mechanism. There is formed integrally with the hollow body 7, or appropriately attached thereto, a chambered extension 13 within which a motor wheel is appropriately mounted, of which 14 is the shaft. The steam pipe for this motor is marked 15 and the exhaust pipe 16. Since the speed of such a motor may be greater than that desirable, for that of the abrading wheel, there is fixed on the motor shaft 14 a pinion 17, that meshes with an intermediate gear 18 on whose shaft is a pinion 19 that meshes with a gear 20 on shaft 9. This train of reducing gear is contained 30 in a chamber 21 formed also on the side of casting 7.

Any suitable means of controlling or governing the speed of the motor may be employed. It is desirable to control it in order that the amount of graphite supplied may be regulated.

Particles of the finely divided graphite will lodge in any crevice, and if an incipient leak exists the draft or suction thereof will 40 directly carry the particles of graphite to and into the crevices and so build up therein a plug or packing that will effectively stop the leak. Of course, the finely divided graphite so fed to the superheating 45 units will, in part, be carried by the steam entirely through the superheating system and be delivered with the steam, in which it is in suspension, to the steam chest of the

locomotive and ultimately to the valves and piston and cylinder surfaces, serving 50 to effectively lubricate the same after the manner set out in the before mentioned patent.

A further feature of the system herein disclosed is that the graphite will form a 55 thin film or coating on the interior surfaces of the superheating units and prevent or reduce the deposit of scale thereon, thereby maintaining the efficiency of the superheating system of the boiler. 60

I claim:

1. In a steam superheater, the combination with superheating tubes and a header in which they are connected, of means for supplying saturated steam to the header 65 and means for delivering finely divided graphite in an attenuated stream to the saturated steam.

2. The combination with a steam superheater comprising a saturated steam pipe, 70 a manifold connected with said pipe, and a plurality of superheating units joined to the manifold; of means for introducing finely divided graphite into that part of the superheater through which the superheated steam passes whereby the insoluble particles of graphite are caused to close steam-tight incipient leaks in the joints of the superheating units. 75

3. In a steam superheater, the combination with a saturated steam pipe, a plurality of superheating units and a manifold connecting the saturated steam pipe and such units, of a connection extending from the saturated steam pipe, means for introducing finely divided graphite into said connection and a steam actuated motor for driving said graphite supplying means and means for supplying steam to the motor. 80 85

In testimony whereof, I have hereunto 90 subscribed my name.

LEWIS S. WATRES.
